EX

No. 12,142

JAN 18, 1881

UNITED STATES PATENT OFFICE.

GEORGE WILKINSON, OF PROVIDENCE, RHODE ISLAND, ASSIGNOR TO
GORHAM MANUFACTURING COMPANY, OF SAME PLACE.

DESIGN FOR SPOON AND FORK HANDLES.

SPECIFICATION forming part of Design No. 12,142, dated January 18, 1881.

Application filed August 28, 1880. Term of patent 7 years.

To all whom it may concern:

Be it known that I, GEORGE WILKINSON, of the city and county of Providence and State of Rhode Island, have invented a new and original Design for the Handles of Spoons and Forks in Silver and Plated Wares, of which the following is a specification.

In the accompanying photograph, A represents a front view of the design, the outline of which is an essential feature. The upper portion, at the point designated 1, is a floral decoration raised from the surface of the handle, over which is a semicircular line of raised beads. At the point designated 2 is a decoration in the form of a rosette. At each of the points designated 3 and 4 is an ornamental transverse band. The section of the handle extending from 3 to 4 consists of a series of curved lines running from the edge of the handle on either side toward the middle line of the handle. At the termination of

the handle, at the point designated 5, the ornamentation is in the form of raised corrugations, tapering as they approach the end of the handle.

Figure B represents the reverse view of the design. At the point designated 6 the ornament consists of a rosette. At the point 7 the ornament is of a shell-like form.

The several features of ornamentation above described are to be substantially such as shown in the accompanying photographic illustration.

I claim as my invention—

The design for spoon and fork handles, consisting of the parts 1, 2, 3, 4, 5, 6, and 7, substantially as herein shown.

GEORGE WILKINSON.
